BOILER

Anthony Kazlauskas, Chicago, Ill.

Application June 5, 1933, Serial No. 674,295

7 Claims. (Cl. 110—97)

My invention relates to boilers and has among its objects and advantages the provision of increased heating efficiency through the effective utilization of the ordinarily wasted products of combustion. The invention further embodies a novel adaptability to boilers of standard construction already installed.

In the accompanying drawings:

Figure 1 is a side elevation of a heating system according to the invention;

Figure 2 is a transverse sectional view along the line 2—2 of Figure 5;

Figure 3 is a fragmentary view of a deflector;

Figure 4 is a sectional view along the line 4—4 of Figure 5; and

Figure 5 is a longitudinal sectional view.

In the embodiment selected to illustrate my invention, I make use of a boiler 10 comprising the usual fire box portion 12 and fire tube portion 14. A housing 16 encloses the boiler with the exception of doors and dampers associated with the front end, and has its walls spaced from the boiler to provide a chamber 18 around the enclosed portions of the boiler. Thus the products of combustion pass through the flues 20 and accumulate in the chamber 18. A partition 22 defines the bottom of the chamber 18 and is positioned above the floor line 24 substantially in a plane common with the grate in the fire box, thus providing a space 26 communicating with a chimney 28. In Figures 4 and 5, the partition 22 terminates at 30 upon each side of the boiler to provide openings 32 establishing communication between the spaces 18 and 26.

Thus the products of combustion entering the chamber 18 between the end of the boiler and the housing 16 pass upwardly and rearwardly around the top and sides of the boiler, downwardly through the openings 32 and into the chimney 28 through the space 26. Referring to Figure 4, it will be noted that the portion 34 of the housing tapers in the direction of the chimney 28, thus eliminating wall surfaces at right angles to the direction of movement of the gases, which would tend to impede the flow of gases.

The volume of the chamber 18 is sufficiently large to insure low velocity, so that thermoconvection is an important factor in the movement of the gases within the chamber and with respect to their exit. The capacity of the chamber 18 should not be less than the volume of the fire box, thus insuring good circulation of the gases. In designing the housing 16 to provide a space 55 around the sides and top of the boiler, the hot

test gases engage the boiler around the steam space so that relatively dry steam is delivered at all times. Thus the gases tend to move downwardly as they are cooled, and the gases leaving the chamber 18 through the openings 32 are too cool to do any evaporating. Furthermore, the chamber 18 provides a secondary combustion chamber of high temperature, so that substantially complete burning of the ordinarily wasted unburned products of combustion is attained. 5 However, the heat of the gases entering the chamber 26 is utilized to warm the partition under the boiler and thus cut down on the loss of heat from that portion of the boiler. These gases also tend to warm the floor surrounding the 10 heating system and help keep it dry.

In Figures 2 and 3, I illustrate a deflector 36 upon each side of the boiler having the lower edges spaced from the partition 22 as at 38. The deflectors are arranged to deflect the gases entering the chamber 18 toward the top of the chamber so that the warmest gases will always engage the upper portions of the boiler. Ordinarily the gases entering the chamber 18 will move to the top of the chamber and pass downwardly as they are cooled and influenced by draft. The deflectors insure movement of the hottest gases over the hottest parts of the boiler at times when a strong draft might draw the gases out of the chamber about the lower side walls 30 of the boiler before they have ascended to the upper part of the chamber. The spaces 38 separate the deflector 36 and the partition 22 so that there can be no pockets which might impede efficient movement of the gases in the compartment 18, thus permitting thermoconvection to influence in a large degree the movement of the gases downwardly about the boiler, with uniform heat transfer along different levels throughout the full length of the boiler. Movement of the 20 gases in this manner, with no pockets inside the housing, prevents the accumulation of stagnant gases, many of which are relatively heavy and tend to separate from the remaining gases. In other words, the gases move in a path tending to 25 sweep the compartments clean, thus eliminating the danger of gas explosions, which are quite 30 frequent when oil is burned.

The housing 16 comprises two brick walls 40 and 42 spaced apart to receive an insulating 50 material 44.

Referring to Figures 2 and 5, I place a sheet of cattle hair felt 46 adjacent the insulation 44 throughout the arched portion of the housing 16, which felt is of a thickness designated in 55

the trade as $\frac{1}{2}$ inch. It will also be noted that I provide an outer plaster coat 48 over the top of the housing substantially coextensive with the felt 46. I prefer to use a plaster analogous to 5 the insulating material 44 with the exception of the cinders. Thus the area of the housing 16 subjected to the highest temperature is provided with additional insulation.

To insure thorough combustion of the unburned gases passing from the flues 20, I provide 10 a pipe 50 having a nozzle 52 arranged to deliver a supplemental air jet in the path of the burning gases. This pipe passes downwardly through the partition 22 and through the housing 16 (see 15 Figures 1 and 2) and is provided with a damper 54 controlling the movement of air through the pipe. This damper, as well as the damper 56 controlling the chimney 28 and the fire door 58, is automatically adjusted by the controlling device 20 60. Devices of this type are well known in the art and need not be described in detail. The weighted lever 62 is connected with the dampers 54 and 56 and the fire box door 58 through the medium of cables 64, 66 and 68, respectively. In 25 Figure 5, I illustrate a feed pipe 70 for the boiler and in Figure 1, I illustrate hot water and steam pipes 72 and 74, respectively. Manholes may be provided in the brickwork to permit access to manholes in the boiler.

Without further elaboration the foregoing will 30 so fully explain my invention that others may, by applying current knowledge, readily adapt the same for use under various conditions of service.

I claim:

- 35 1. In combination with a fire tube boiler having a single pass for the products of combustion, a housing enclosing the entire outer boiler shell except the fire box door and defining a chamber lying above and on both sides of the boiler shell and an enclosed space beyond the end of the boiler pass in open communication with said chamber, a partition defining the lower limits of said chamber and space and lying immediately below the bottom of said shell, said housing having an end wall, said partition terminating on either side of the fire box short of the end wall of said housing to define a downwardly opening exit, and side walls and a floor cooperating with said partition to define an exit for the spent gases of combustion, and exhaust means in the nature of a stack for withdrawing the spent gases from said exit, said side walls including inclined portions defining a tapered entrance to said exhaust means.
- 45 2. In combination with a fire tube boiler having a single pass for the products of combustion, a housing enclosing the entire outer boiler shell except the end at the fire box door and defining a chamber lying above and on both sides of the boiler shell and an enclosed space beyond the end of the boiler pass in open communication with said chamber, a partition defining the lower limits of said chamber and space and lying immediately below the bottom of said shell, said housing having an end wall, said partition terminating on either side of the fire box short of

the end wall of said housing to define a downwardly opening exit, and side walls and a floor cooperating with said partition to define an exit for the spent gases of combustion.

3. The combination with a boiler, of a housing 5 substantially enclosing the same and arranged in spaced relation therewith, said boiler comprising a fire box portion and a fire tube portion, a partition within said housing dividing the space around the boiler into an upper compartment and 10 a lower compartment and terminating short of one end of the boiler, to provide openings establishing communication between the two compartments, the fire tube portion lying within the upper compartment, deflecting means within said housing for deflecting products of combustion emerging from the fire tube portion toward the upper part of said upper compartment, and a stack communicating with said lower compartment for withdrawing the spent gases. 20

4. In a steam generator, a liquid receptacle, an enclosure housing said receptacle, said enclosure including walls spaced from said receptacle, and another wall not so spaced having an outer surface wholly outside of said receptacle, and conduit means for passing spent gases coming from said enclosure along the outer surface of said last mentioned wall. 25

5. In combination with a boiler having a shell and fire tubes, enclosure means for said boiler so constructed and arranged that products of combustion pass through said fire tubes, emerge therefrom and then pass back in a generally longitudinal direction in a stream along the outside of the shell of said boiler, and means so constructed and arranged that a fraction of said longitudinal stream is shunted away therefrom, passed in a generally circumferential direction along the outside of said boiler shell and then returned to intermingle with the products of combustion emerging from said fire tubes. 30 35 40

6. In combination with an approximately horizontal boiler having a shell and fire tubes having discharge openings at one end of said boiler; enclosure means for said boiler comprising a bottom wall directly underlying said shell, and side and top walls spaced from said shell and forming a U-shaped chamber, and an end wall, at said discharge end of said fire tube boiler, spaced from said shell and forming an end space 45 50 in open communication with said chamber at said end space; and baffles, spaced from said bottom wall, extending transversely across said chamber at both sides of said boiler.

7. In a fire tube boiler having a shell, walls defining passages for the products of combustion, a partition, extending longitudinally of said boiler shell, underneath said boiler shell, said partition at its upper face covering a portion of the outer surface of said boiler shell, and an exit passage-way for conveying the spent gases along the opposite face of said partition, to warm said opposite face and reduce the rate of loss of heat from that portion of the boiler. 55 60 65
